UNITED STATES PATENT OFFICE.

JOHN L. BERGER, OF DENVER, COLORADO, ASSIGNOR OF ONE-FOURTH TO
GEORGE ANDERSON, OF DENVER, COLORADO.

HOT-AIR FURNACE.

No. 853,153.

Specification of Letters Patent.

Patented May 7, 1907.

Application filed June 12, 1905. Serial No. 264,760.

To all whom it may concern:

Be it known that I, JOHN L. BERGER, a citizen of the United States, residing in the city and county of Denver and State of Colorado, have invented certain new and useful Improvements in Hot-Air Furnaces; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in hot air furnaces, my object being to utilize to the best advantage the heat from the fire box, to the end that the maximum saving may be made thus economizing fuel. I accomplish this by a construction having an increased heat radiating surface exposed to the air to be heated, as compared with furnaces of ordinary construction.

Having briefly outlined my improved construction as well as the function it is intended to perform, I will proceed to describe the same in detail reference being made to the accompanying drawing in which is illustrated an embodiment thereof.

In this drawing, Figure 1 is a vertical longitudinal section taken through the furnace on the line 1—1 Fig. 2. Fig. 2 is a horizontal section taken on the line 2—2 Fig. 1. Fig. 3 is a detail sectional view upon an enlarged scale showing one of the tubes employed. Fig. 4 is a sectional view of a part of the furnace illustrating a modified form of construction.

Attention is called to the fact that in Figs. 1, 2 and 4 of the drawing, the dotted arrows indicate the course of the products of combustion, while the full line arrows indicate the course of the air to be heated.

The same reference characters indicate the same parts in all the views.

Let the numeral 5 designate the outer casing of the furnace; 6 the fire box; 7 the grate and 8 the ash pit. Mounted above the fire box and supported thereby is a chamber 9 having an annular space 10 communicating by short pipes 12, with a space 13 for the air to be heated, the space 13 being located between the casing 5 and the fire box. The space 10 has no communication with the

products of combustion from the fire box. 55 The lower part of the chamber 9 is provided with a circular inclined plate 14 having openings communicating with the pipes 12, the said plate being formed integral with the pipes. The upper edge of the plate is 60 grooved, to receive the lower edge of the wall of a chamber 15 surrounding the chamber 9, the latter being located in the lower part of the chamber 15. The top of the annular chamber 9, is provided with openings which 65 register with vertically disposed pipes 16, whose upper extremities pass through openings formed in the top wall of the chamber 15. The air to be heated after entering the annular chamber 10, passes through the 70 pipes 16, and thence into the upper part of the air space surrounding the chamber 15, and thence out of the openings 17 to the hot air distributing conduits (not shown). The pipes 16 are suitably connected with the chamber 9 in order to form tight joints, whereby 75 communication between the products of combustion and the air to be heated is prevented.

As shown in the drawing the two chambers 80 9 and 15, are provided with apertured ears 18 and 19 respectively, through which are passed bolts 20. A suitable quantity of packing material designated 21, is placed in the groove in the upper edge of the plate 85 14, in order to form a tight joint. The top and side walls of the chamber 15 are connected by means of bolts 22 or other suitable fastening devices.

From the foregoing description the use of 90 the furnace as thus far described will be readily understood. The heat and products of combustion from the fire box, pass upwardly within the chamber 15, surrounding the chamber 9 and the pipes 16, the products of 95 combustion finally escaping through the smoke flue 24. It will thus be seen that by reason of the chamber 9 and the pipes 16 (the latter forming a multiple tube conduit for the air to be heated,) there is a considerable surface area exposed to the action of the heat. The air to be heated entering through the cold air duct 25, first passes to the space 13 between the casing 5 and the fire box, thence through the short pipes 12 to the space 10 of 100 the chamber 9, and thence through the tubes 16 to the hot air space above the chamber 15. The air to be heated also passes around the 105

chamber 15, as well as through the chamber 9 and the tubes 16, presenting a very extensive heat radiating surface to the air, the object being as aforesaid to utilize the heat from the fire box to the best advantage, and reduce the temperature of the products of combustion to the lowest practicable degree before allowing them to escape to the smoke flue.

In the form of construction shown in Fig. 4, a single conduit 26 is located within the chamber 15 and connected with the chamber 9. In this view is also shown a hollow core 27 located within the large tube 26, this hollow core being closed at the top and open at the bottom to the products of combustion. This hollow core 27 may be used or not as desired. If it is not used of course some other means must be employed to close the central opening 28 through the chamber 9, in order to prevent the products of combustion from the fire box from mingling with the air to be heated. In this form of construction the air to be heated enters the chamber 9 in the same manner as heretofore explained, and passes thence up through the tube 26, as well as around the chamber 15; while the products of combustion from the fire box, pass upwardly into the chamber 15 around the large tube 26 and finally out through the smoke pipe 24. These products of combustion also enter the hollow core 27 when the latter is employed. This tube 27 presents additional heat-radiating surface to the air passing through the tube 26.

The upper part of the chamber 9, is preferably downwardly inclined in both directions as shown in Fig. 1, in order to prevent the accumulation of soot or dirt, upon the top of the said chamber. By reason of these sloping sides as indicated at 9^a, the soot, dirt and other material, which otherwise would have a tendency to lodge upon the top of the chamber 9, readily slip downwardly therefrom and enter the fire box.

In further explanation of the connection between the tube 16 and the chambers 9 and 15, it may be stated that the lower extremity of each tube 16 is surrounded by a collar A fastened to the circular apex 9^a of the chamber 9. The lower part of the tube within the collar A is provided with a circular rib B which is so located as to occupy a position about midway of the height of the collar A. The space between the lower extremity of each tube 16 and the collar A is filled with a suitable packing material C for the purpose of making a perfectly tight joint. The upper extremity of each tube 16 is threaded externally as shown at D where it passes through an opening formed in the top of the chamber 15. This tube is connected with the top wall

of the chamber 15 by means of nuts E and F applied to the tube above and below the top plate of the chamber. The upper interior corner of the nut F is cut away to make room for a quantity of packing material G which in connection with the washer H forms a tight joint around the tube.

Having thus described my invention, what I claim is:

1. In a hot air furnace, the combination with a fire box, of a products-of-combustion chamber located above the fire box, an air chamber interposed between the products-of-combustion chamber and the fire box and having a circular apex at its top provided with openings, collars surrounding said openings, tubes whose lower extremities enter the collars, means for forming an air tight joint between the tubes and the collars, the top of the products-of-combustion chamber being provided with openings to receive the upper extremities of the tubes whose ends are threaded, nuts applied to the threaded extremities of the tubes above and below the top of the products-of-combustion chamber, and means for forming an air tight joint between the threaded extremities of the tube and the top of said chamber.

2. In a hot air furnace, the combination with an outer casing and a fire box, of a products-of-combustion chamber located above the fire box, an air chamber interposed between the fire box and the products-of-combustion chamber, the air chamber being formed at the top with an apex whose downwardly sloping sides are considerably inclined, the said apex being provided with openings, tubes whose lower extremities register with said openings, the top of the products-of-combustion chamber having openings to receive the upper extremities of the tubes, and suitable means for forming air tight joints between the tube extremities and the parts with which they are connected.

3. In a hot air furnace, the combination with an outer casing and a fire box, of a products of combustion chamber located above the fire box, an air chamber interposed between the fire box and the products of combustion chamber, the air chamber being formed at the top with an apex whose downwardly sloping sides are considerably inclined, the said apex being provided with openings, and tubes whose lower extremities register with said openings.

In testimony whereof I affix my signature in presence of two witnesses.

JOHN L. BERGER.
